UNITED STATES PATENT OFFICE

1,997,454

PRINTING

Salvatore J. Culetta, Chicago, Ill.

Application January 27, 1934, Serial No. 708,620

5 Claims. (Cl. 101—399)

This invention relates to printing.

It is an object of this invention to provide an improved printing which is relatively simple and inexpensive in construction and efficient in use.

The excellence and merit of printing are judged to a large extent by the attractiveness of physical make-up and the attention given to details which contribute finesse to the printing.

An objectionable feature that has heretofore existed in the composition of type and which detracts very considerably from the nicety and appearance of type composition, is the use, in conjunction with quotation marks, of a punctuation mark printing characters such, for example, as a comma or a period, cast on a type body separate from that on which the quotation mark or marks are cast and spaced laterally or horizontally therefrom, so that the counterpart or inscription of the punctuation mark character when printed is either preceded or followed by a quotation mark or marks, thus: —,” or “—,” or “—”, or “—”; thereby causing an otherwise properly spaced line or printing to appear unequally spaced on account of the lack of vertical alignment between the punctuation mark and the quotation mark, and the marks, and the resulting blank space therebetween. This arrangement not only is relatively expensive, requiring the use of two separate type bodies, but is especially objectionable and an eyesore when a punctuation mark and a quotation mark or marks occur at the end of a line, and also when several short, quoted phrases are used in sequence in a single sentence, as for example: “Swanee River”, “Desert Song”, and “Aloha”.

It is, therefore, an object of the present invention to overcome and correct the aforementioned and other objectionable features existing in this phase of the prior art of printing.

Another object of the present invention is to provide a combination type body or printing character having properly spaced and aligned on its printing face both a punctuation mark and a quotation mark, thereby eliminating the use of two separate type bodies to print these characters.

A further object of the present invention is to provide a new and improved type body, for the purposes herein set forth, and having cast integrally therewith, in vertical alignment, both a punctuation mark character and a quotation mark character.

Other objects will appear hereinafter.

The drawing illustrates two typical embodiments of the invention and therein:

Fig. 1 is a perspective view illustrating the in-

vention as embodied in one of the new type bodies which has formed on its printing face both a combination quotation mark and punctuation mark printing character;

Fig. 1A is a view showing the inscription made by the type body shown in Fig. 1;

Fig. 2 is a perspective view illustrating the invention as embodied in one of the new type bodies bearing on its printing face both another form of the combination quotation mark and punctuation mark printing character; and

Fig. 2A is a view showing the inscription made by the type body shown in Fig. 2.

A typical embodiment of the present invention is illustrated in Fig. 1 of the drawing wherein one of the new type bodies is generally indicated at 10 and comprises a body 11 of metal or other suitable material having a printing face 12 upon which is formed, as illustrating and embodying one form of the present invention, a combination quotation mark and punctuation mark printing character; the printing character being formed integrally with the type body 11 on the printing face of the latter.

The combination character includes single quotation mark character 13 and a combination character in the form of a comma 14, and the counterpart or inscription made by this printing character 13—14 is shown to the right thereof in Fig. 1 and is indicated at 15—16. From an examination of Fig. 1 it will be observed that the combination character 13—14, in addition to being cast as integral parts of one type body, rather than upon separate type bodies, which in itself effect a distinct economy, has its constituent elements 13—14 vertically aligned so that when the inscription 15—16 is made thereby it brings about a neat attractive, and harmonious appearance of the quotation and punctuation marks 15—16, respectively, as illustrated by the following examples: “Aloha”, and “Desert Song.” Which, compare with the prior art arrangement of: “Aloha”, and “Desert Song.” It will be readily observed from this comparison that the new arrangement is much more attractive and pleasing to the eye and enables the eye to focus itself much more readily thereon than does the prior art arrangement. Hence the present invention overcomes the aforementioned and other objectionable features of this phase of the prior art of printing.

In addition, the arrangement of the quotation and punctuation marks 15 and 16, in vertical alignment, one above the other, eliminates controversial opinion as to whether the comma or period should be placed before or after the

quotation mark or marks, since in vertically aligned arrangement of the present invention, there is no alternative.

Fig. 2 illustrates another embodiment of the invention and therein one of the new type bodies is generally indicated at 17 and comprises a body 18 of metal or other suitable material having a printing face 19 upon which is formed a raised combination printing character 20—21, the printed counterparts or inscriptions of this character being shown at 22 and 23, respectively, and having the advantages herebefore set forth relative to the type body 10.

While the invention has been illustrated as embodying a combination character made up of single quotation mark and a single punctuation mark in the form of commas and periods, it is indicated that the invention also contemplates the use of combination characters including double quotation marks and other punctuation marks than those shown, such, for example, as colons, semi-colons, question marks, etc.

The notches 24 in the type bodies 10 and 17 are conventional and for use in locking the type bodies in printing position.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A type body including a printing face having formed thereon integrally with said body a combination printing character consisting of a quotation mark character and a punctuation mark character arranged below said quotation mark character and in vertical alignment therewith relative to the vertical axis of said type body so that when said combination character is printed the counterparts or inscriptions formed by its aforementioned constituents will be arranged in vertical alignment one above the other in the above-named order on the inscription-receiving member.

2. A type body including a printing face having formed thereon integrally with said body a

combination printing character consisting of a quotation mark character and a punctuation mark character in the form of a period arranged below said quotation mark character and in vertical alignment therewith relative to the vertical axis of said type body so that when said combination character is printed the counterparts or inscriptions formed by its aforementioned constituents will be arranged in vertical alignment one above the other in the above-named order on the inscription-receiving member.

3. A type body including a printing face having formed thereon integrally with said body a combination printing character consisting of a quotation mark character and a punctuation mark character in the form of a comma arranged below said quotation mark character and in vertical alignment therewith relative to the vertical axis of said type body so that when said combination character is printed the counterparts or inscriptions formed by its aforementioned constituents will be arranged in vertical alignment one above the other in the above-named order on the inscription-receiving member.

4. A type body including a printing face having formed thereon integrally with said body a combination printing character consisting of a single quotation mark character and a punctuation mark character in the form of a period arranged below said quotation mark character and in vertical alignment therewith relative to the vertical axis of said type body so that when said combination character is printed the counterparts or inscriptions formed by its aforementioned constituents will be arranged in vertical alignment one above the other in the above-named order on the inscription-receiving member.

5. A type body including a printing face having formed thereon integrally with said body a combination printing character consisting of a single quotation mark character and a punctuation mark character in the form of a comma arranged below said quotation mark character and in vertical alignment therewith relative to the vertical axis of said type body so that when said combination character is printed the counterparts or inscriptions formed by its aforementioned constituents will be arranged in vertical alignment one above the other in the above-named order on the inscription-receiving member.
